Inventor
B. W. Johnson.

By Attorney

UNITED STATES PATENT OFFICE.

BURT W. JOHNSON, OF LANSING, MICHIGAN.

TOBACCO PIPE.

Application filed July 13, 1922. Serial No. 574,608.

To all whom it may concern:

Be it known that I, BURT W. JOHNSON, a citizen of the United States, residing at Lansing, in the county of Ingham and State 5 of Michigan, have invented certain new and useful Improvements in Tobacco Pipes; and I do hereby declare the following to be a full, clear, and exact description of the invention, such as will enable others skilled 10 in the art to which it appertains to make and use the same.

The object of the present invention is to eliminate mouth moisture and insure a dry 15 and clean smoke and obviate fouling of the pipe and the collection of fluid therein.

Other objects and advantages will be apparent and suggest themselves as the nature 20 of the invention is understood.

While the drawings illustrate an embodiment 25 of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a perspective view of a tobacco 30 pipe embodying the invention,

Figure 2 is a top plan view of the end, showing the parts on a larger scale,

Figure 3 is a detail perspective view of 35 the tip of the stem, the valve being detached,

Figure 4 is a detail perspective view of the valve, and Figure 5 is a cross section on the plane indicated by the line 5—5 of Figure 4.

Corresponding and like parts are referred 40 to in the following description and designated in the several views of the drawings by like reference characters.

The tobacco pipe illustrated is of ordinary 45 construction and has been selected to demonstrate the application of the invention. The tip of the stem 1 is enlarged as indicated at 2 to be engaged by the lips or teeth whereby to conveniently hold the

pipe in the mouth. A groove 3 is formed 50 in the upper portion of the enlargement or flange 2 to receive the ear 4 of a flap valve 5 which is disposed to cover the end of the stem 1 and close the opening therein through which the smoke is drawn. A pintle 6 pivotally connects the valve 5 to the stem and passes through the ear 4 and part of the enlargement or flange 2 adjacent and bordering upon the groove 3.

The valve 5 may be of any material and 55 is pivoted to open upwardly and close downwardly and normally remain closed by gravitational action. The valve is of concavo-convex form and arranged with the hollow side adjacent the end of the stem 60 so as to prevent sticking and insure a free movement so as to readily open by suction when smoking and positively close and prevent any moisture from entering the stem when the pipe is inert and no smoke being 65 drawn therethrough. The valve 5 responds readily so as to open quickly for the passage of the smoke and to close instantly when suction ceases, thereby preventing the breath or moisture passing from the mouth 70 into the opening of the stem with the result that a clean dry smoke is assured.

What is claimed is:

1. A pipe stem having a valve pivotally mounted at the mouth end and adapted to 80 open and close during smoking, said valve being exteriorly convexed and exposed for direct engagement by the tongue, and said valve being interiorly concave.

2. A pipe stem having its mouth end provided with a groove, a valve for closing the mouth end and having an ear engaging in said groove, and a pintle engaging the stem and an opening in the ear to permit the valve to open and close, said valve being 90 concavo-convex in form for the purpose stated.

In testimony whereof I affix my signature in presence of two witnesses.

BURT W. JOHNSON.
